(57) **CLAIM**

The ornamental design for a display screen with graphical user interface, as shown and described.

DESCRIPTION

FIG. 1 is a front view of a first embodiment of a display screen with graphical user interface showing our new design;

FIG. 2 is a front view of a second embodiment of a display screen with graphical user interface showing our new design;

FIG. 3 is a front view of a third embodiment of a display screen with graphical user interface showing our new design; and,

FIG. 4 is a front view of a fourth embodiment of a display screen with graphical user interface showing our new design.

The broken lines showing the display screen and portions of the graphical user interface form no part of the claimed design.
